Primary Examiner — Ramzi S Almatrahi(74) *Attorney, Agent, or Firm* — Volpe and Koenig, P.C.(57) **CLAIM**

The ornamental design for a monitoring camera, as shown and described.

DESCRIPTION

FIG. 1 is a perspective view of a monitoring camera in accordance with our design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a bottom plan view thereof.

The broken lines depict portions of the monitoring camera in which the design is embodied that form no part of the claimed design. Additionally, the dash-dot-dot lines denote the boundary of the claim and form no part of the claimed design.
